JOHN HERD METHVEN, OF RONALD, WASHINGTON.

OIL-CUP AND FEEDING ATTACHMENT THEREFOR.

1,259,264.

Specification of Letters Patent.

Patented Mar. 12, 1918.

Application filed June 25, 1917. Serial No. 176,763.

To all whom it may concern:

Be it known that I, JOHN H. METHVEN, a subject of the King of England, and a resident of Ronald, in the county of Kittitas 5 and State of Washington, have invented a new and useful Improvement in Oil-Cups and Feeding Attachments Therefor, of which the following is a specification.

My present invention relates generally to 10 oil feeding devices, and more particularly to oil cups and attachments therefor, the combined operation of which effectively prevents the feeding of impurities with the lubricant and the construction of which obviates clogging up of the feed pipe by impurities in the oil within the cup.

Generally speaking I obtain these advantages by an arrangement which includes an oil cup in which the feed pipe is extended to 20 a point adjacent the upper end of the cup, together with a water tank which in operative position provides the necessary pressure to lift the body of oil to the receiving end of the feed pipe, and manipulation of which 25 to inoperative position permits of the draining of the water and refilling of the oil cup.

More especially my invention resides in the construction, arrangement, and operation of parts as shown in the accompanying 30 drawing to which reference is made in the following specification embodying a description of the invention.

In the drawings:

Figure 1 is a view partly in side elevation and partly in section, illustrating my improvements;

Figs. 2 and 3 are detail sectional views taken respectively on lines 2-2 and 3-3 of Fig. 1;

Fig. 4 is a detail section through the filling cap and relief port of the water receptacle.

Fig. 5 is an edge view of the supporting bracket.

Referring now to these figures, my invention provides an oil cup generally indicated at 10, having its feed pipe 11 provided with sight feed glasses 12, as seen particularly in Fig. 3, and with a cutoff valve 13, 50 and having its upper end extended upwardly within the oil cup 10 to a point adjacent the upper end of the latter, and threaded at 14.

The cylindrical portion 15 of the oil cup is of glass and its top 16 has an outer annular flange 17 engaging the upper edge of the cylindrical glass 15 and is provided with an

inner depending threaded ring 18 supported by arms 19 for engagement upon the threaded upper end 14 of the feed pipe, the central portion of the top 16 having a threaded 60 nipple on which is screwed a filling cap 20 adjacent the upper extremity of the feed pipe, upon which latter is a shield 21 of cone-shape, inverted in spaced relation to the upper end of the pipe and connected thereto 65 by a reticulated cylinder 22 so as to permit the lubricant within the body of the oil cup to find its way upwardly over the upper end of the feed pipe and downwardly into the same, and at the same time force the lubricant 70 in such movement to pass through the reticulated material by means of which impurities are rejected.

Adjacent its lower end of the oil cup 10 has a water inlet tube 23 extending and 75 opening therein, to the outer end of which water inlet tube is rotatably connected the end of the tube 24, the connection being made by a packed joint 25 to obviate leakage. The tube 24 forms the angular end of 80 a vertically disposed water pipe 26 leading from an enlarged water container 27, in the present instance of substantially a spherical shape, that end of the tube 24 opposite the packed joint 25 having a conical recess in its 85 terminus receiving the similarly shaped end of a bearing pin 28, the latter threaded within the central bearing 29 of a supporting bracket 30, so as to thus permit of rotation of the water receptacle 27 upon the longitudinal axis of the tube 24 from uppermost 90 position above the oil cup 10 to lowermost position below the same and vice versa.

The bracket 30 which generally extends in an upright position and is secured at the 95 outer end of a supporting stem 31 has an upper and lower angular arm 32 and 33 respectively, forming stops for the pipe 26 of the water receptacle, and provided with pivoted catches 34 to engage the said pipe for 100 holding the water receptacle in upper and lower positions.

The water intake pipe 23 is preferably provided with a cut-off valve 35 so that when the water receptacle 27 is turned down 105 to the lower position and the water allowed to drain into the vessel and out of the oil cup previous to refilling the latter, the said valve may be closed when the oil is poured into the cup upon removal of the filling cap 110 20. In this operation the water is drained back into the water receptacle to the level

of the inner upturned end of the water tube 23 of the oil cup and the latter may be then drained of the remaining water including residue by means of a drain nipple 36 normally closed by a cap 37.

As above stated, the oil is introduced after lowering of the water receptacle to permit the water to flow back thereinto from the oil cup, and in case the water remaining in the oil cup is drained out, the lower portion of the cup is filled with water to the level of the inner end of the tube 23 before the supply of oil is introduced through the filling aperture.

15 It is obvious that my invention provides an oil filling device of this type in which refilling of the oil cup may be accomplished readily and quickly at all times, the supply of oil standing in the feed pipe and controlled by its regulating valve 13, taking care of the proper lubrication of the parts in connection with which the invention is utilized, during the short space of time required for refilling.

25 It is furthermore obvious that the invention provides a comparatively simple and inexpensive device of this type, durable in its nature and capable of effective and efficient use for the intended purposes.

30 The container 27 before referred to may have a filling cap and relief port 27^a, as seen in Fig. 4, provided with a check valve 27^b to prevent outflow of water.

I claim:—

35 1. In an oil feeding device of the character described the combination of an oil cup

having an oil feed pipe extending upwardly thereinto and opening at its upper end within the upper portion of the oil cup, the said upper end of the feed pipe being 40 threaded, and the said oil cup including a top plate having a depending threaded ring for engagement with the threaded portion of the pipe and provided with an upstanding threaded nipple, a filling cap threaded 45 upon the nipple, a shield inverted in spaced relation above the upper end of the feed pipe, a reticulated cylindrical section connecting the shield with the upper end of the feed pipe to prevent the entrance of impurities and means for feeding a liquid heavier than oil into the lower end of the cup.

2. A liquid feeding device for oil cups including a horizontally disposed feed tube in two parts having a rotatable connection permitting the movement of one part with respect to the other, a supporting bracket, an adjustable bearing member having a threaded connection with the bracket and engaging the rotatable portion of the tube to support the same in its rearward movement, a liquid holding receptacle, a feed pipe connecting the receptacle with the rotatable portion of the feed tube and movable therewith, and means connected to portions of the 60 said supporting bracket for holding the liquid receptacle in upper and lower positions.

JOHN HERD METHVEN.
